UNITED STATES PATENT OFFICE.

FRANK EBERHART AND CHARLES A. SCHUBERT, OF NEW YORK, N. Y.

OVEN-DOOR.

SPECIFICATION forming part of Letters Patent No. 656,839, dated August 28, 1900.

Application filed June 20, 1898. Serial No. 684,028. (No model.)

To all whom it may concern:

Be it known that we, FRANK EBERHART and CHARLES AUGUST SCHUBERT, of New York city, New York, have invented a new and useful Improvement in Oven-Doors, of which the following is a specification.

Our invention relates to bakers' ovens, and has for one object to provide means whereby moisture may be imparted to the heated air within the baking-chamber.

Another object is to provide improved means for mounting a sight upon the front wall of the oven, and by the manipulation of which moisture collecting upon the same from the oven-chamber may be readily removed.

To this end the invention consists, substantially, in the construction, combination, and arrangement of parts, as will be hereinafter fully described, illustrated, and claimed.

In the accompanying drawings, Figure 1 is a front view of the oven with the front plate removed. Fig. 2 is a front elevation of the front plate removed and showing our improved sight. Fig. 3 is a top view of the handle of the oven-door. Fig. 4 is a transverse section of the front part of the oven, showing the upper steam-chamber.

Referring to the drawings, A designates a horizontally-swinging door provided with a central balancing-weight B, secured to one end of the fulcrum-rod E of the door and held thereon by means of a rod D, fitted in a central vertical opening in the weight B, and which rod is provided with a socket at its lower end to receive the fulcrum-rod E. This weight is further provided with outwardly-projecting lips having sockets X and X' to receive a handle C. When the handle is grasped and pulled forward, the counterbalancing-weight B equalizes the weight of the door, and hence only a slight pull to open the door is necessary.

Located at one side of the door A is a steam-separating chamber F, into which steam is admitted through the pipe Q. The purpose of this chamber F is to separate the moisture from the steam, the water of condensation being removed through the pipe H, while the

light and dry steam enters the pipes G and R and is conducted to the chamber L at the top 50 of the oven, where it is distributed into the upper portion of the oven-chamber through the openings in the rear or inner wall of the chamber L. These pipes G and R are of unequal length, one entering the chamber near 55 its end, while the other extends farther into the central part of the chamber, thereby distributing the steam through the entire space of chamber L.

A plate T, having bolt-holes T', is secured 60 to the front of the oven and covers the upper front edge of the baking-chamber, as shown in Fig. 4, and is placed between the chamber L and the top edge of the door. This plate T is further provided with a longitudinal dove-tailed groove T'', into which is fitted a correspondingly-shaped slide O, carrying a transparent sight J. Near one end of the groove T'' is an opening S, of the same size and shape as the sight J, and to one side of said opening is embedded a filling of asbestos cloth K, which serves as a wiper for the sight J. When the view through the sight is obstructed by the collection of moisture upon the inner face of the same, the slide O is drawn to the position shown in Fig. 2, and when returned to its normal position, which is when the sight J alines with the opening S, it has been freed of the moisture by the wiper K.

Having thus described our invention, what 80 we claim, and desire to secure by Letters Patent, is—

1. In an oven, the combination with a steam-separator located at one side of the oven-door, of a distributing-chamber above the oven-door, and having a series of perforations through which the steam is discharged to the oven-chamber, of steam-conducting pipes communicating with the two chambers, one of said pipes discharging near the center of 85 the chamber, and the other near its end, whereby the entire chamber is filled with steam before the steam enters the oven.

2. In an oven, the front wall of which is provided with an opening extending into 95 the oven, combined with a sliding sight, and

means for cleaning such sight, substantially as described.

3. An oven provided with a front plate having a groove, and an opening, and a wiper embedded within the groove at one end of the opening, combined with a bar sliding in the groove and carrying a sight, said sight adapted to align with the opening when in a

normal position and contacting with the wiper when reciprocated in the slot.

FRANK EBERHART.
